DESIGN FOR A TOY ARMORED CAR

Atwood E. Erlinder, Chicago, Ill.

Application March 21, 1940, Serial No. 91,120

Term of patent 7 years

To all whom it may concern:

Be it known that I, Atwood E. Erlinder, a citizen of the United States of America, residing at 7658 South Park Avenue, Chicago, Illinois, have invented a new, original, and ornamental Design for a Toy Armored Car, of which the following is a specification, reference being had to the accompanying drawing, forming a part thereof.

Fig. 1 is a side elevational view of a toy armored car showing my new design; Fig. 2 is a top plan view and Fig. 3 is a rear view thereof.

The characteristic features of my design are shown in the full lines in the drawing.

I claim:

The ornamental design for a toy armored car, substantially as shown and described.

ATWOOD E. ERLINDER.
